Primary Examiner—Stella Reid*Assistant Examiner*—Mark Goodwin(74) *Attorney, Agent, or Firm*—Whyte Hirschboeck Dudek SC(57) **CLAIM**

The ornamental design for a blank for making tissue container having an interior reflective surface, as shown and described.

DESCRIPTION

FIG. 1 is a top perspective view of a blank for making tissue container having an interior reflective surface showing our new design;

FIG. 2 is a top plan view thereof;

FIG. 3 is a rear view thereof;

FIG. 4 is a front view thereof;

FIG. 5 is a right side view thereof with the left side view being a mirror image thereof; and,

FIG. 6 is a bottom plan view thereof.

The broken lines shown in the figures are for illustrative environmental purposes only and form no part of the claimed design.
